PANEL FOR A WALL-MOUNTED TELEPHONE OR SIMILAR ARTICLE

Richard H. Wann, Barrington Heights, Ill.
(P.O. Box 514, Barrington, Ill.)

Filed July 8, 1964, Ser. No. 80,760

Term of patent 14 years

(Cl. D26—14)

FIG. 1

FIG. 2

FIG. 3

FIG. 4

FIG. 1 is a perspective view of a panel for a wall-mounted telephone or similar article, showing my new design;

FIG. 2 is a right end elevational view;

FIG. 3 is a top plan view; and

FIG. 4 is a fragmentary rear elevational view, a portion being broken away for convenience in illustration.

I claim:

The ornamental design for a panel for a wall-mounted telephone or similar article, substantially as shown and described.
